Specification for Design.

Patented Apr. 26, 1921.

Application filed May 22, 1920. Serial No. 383,575. Term of patent 14 years.

To all whom it may concern:

Be it known that I, ELUE O. FRITCH, of Belmont, Massachusetts, have invented a new, original, and ornamental Design in Non-Skid Treads for Automobile-Tires, of which the following is a specification, reference being had to the accompanying drawing, forming a part thereof.

In this drawing, Figure 1 is a plan view of a section of the tread showing my new design, and Fig. 2 is a section on line 2—2 of Fig. 1.

I claim:

The ornamental design for a non-skid tread for automobile tires as shown.
